CLAIM

The ornamental design for a dispensing cap for finger pump, as shown and described.

DESCRIPTION

FIG. 1 is an isometric view of my new design for a dispensing cap for finger pump,
FIG. 2 is a front view thereof;
FIG. 3 is a top view thereof;
FIG. 4 is a left-side view thereof;
FIG. 5 is a right-side view thereof;
FIG. 6 is a bottom view,
FIG. 7 is an isometric view of a second embodiment of FIG. 1;
FIG. 8 is a front view thereof;
FIG. 9 is a top view thereof;
FIG. 10 is a right side view thereof;
FIG. 11 is a left side view thereof; and,
FIG. 12 is a bottom view.
